COMBINATION CUTTING AND CRIMPING TOOL

Martin D. Bergan, Westfield, N. J.

Application February 17, 1956, Serial No. 40,203

Term of patent 14 years

(Cl. D54—13)

Fig. 1 is a side elevation of a combination cutting and crimping tool showing my new design;

Fig. 2 is a fragmentary side elevation of the opposite side of the same;

Fig. 3 is a fragmentary elevational view similar to Fig. 2, but showing the jaws in open position;

Fig. 4 is a sectional view taken on the line 4—4 of Fig. 2; and

Fig. 5 is a fragmentary top plan view of the cutting and crimping tool shown in Fig. 1.

I claim:

The ornamental design for a combination cutting and crimping tool, as shown.
